(57) **CLAIM**

(21) Appl. No.: **29/113,665**

The ornamental design for a refrigerant compressor for an air conditioner of vehicle, as shown and described.

(22) Filed: **Nov. 10, 1999**

DESCRIPTION

(30) **Foreign Application Priority Data**

May 10, 1999 (JP) D11-12146

FIG. 1 is a front view of a refrigerant compressor for an air conditioner for a vehicle, according to my design.

(51) LOC (7) Cl. **15-02**

FIG. 2 is a rear elevation view of the refrigerant compressor of FIG. 1.

(52) U.S. Cl. **D15/9**

FIG. 3 is a top plan view of the refrigerant compressor of FIG. 1.

(58) **Field of Search** D15/5, 7-9; D23/354, D23/163, 325, 365; 418/259; 417/359, 415, 410.3, 534

FIG. 4 is a bottom plan view of the refrigerant compressor of FIG. 1.

(56) **References Cited**

FIG. 5 is a left side view of the refrigerant compressor of FIG. 1.

U.S. PATENT DOCUMENTS

FIG. 6 is a right side view of the refrigerant compressor of FIG. 1.
